Primary Examiner — Jae Liang(74) *Attorney, Agent, or Firm* — Wood Herron & Evans LLP(57) **CLAIM**

The ornamental design for a lid for water bottle, as shown and described.

DESCRIPTION

FIG. 1 is an isometric view of a lid for water bottle according to the present invention.

FIG. 2 is a front elevation view thereof.

FIG. 3 is a right-side view thereof.

FIG. 4 is a rear elevation view thereof.

FIG. 5 is a left-side elevation view thereof.

FIG. 6 is a top plan view thereof; and,

FIG. 7 is a bottom plan view thereof.

The broken dash lines in the figures are for illustrative purposes only and represent non-claimed environmental subject matter. Neither the portions of the invention shown in broken dash line nor the broken dash lines themselves form any part of the claimed invention.
